United States Patent Office.

CHRISTIAN RICH, OF MARSHALLSVILLE, OHIO

Letters Patent No. 77,658, dated May 5, 1868.

IMPROVEMENT IN FARM-GATES.

The Schedule referred to in these Letters Patent and making part of the same.

TO ALL WHOM IT MAY CONCERN:

Be it known that I, CHRISTIAN RICH, of Marshallsville, in the county of Wayne, and State of Ohio, have invented new and useful Improvements in Farm-Gates; and I do hereby declare that the following is a full, clear, and exact description of my invention, reference being had to the accompanying drawings, forming a part of this specification, and to the letters of reference marked thereon, of which drawings—

Figure 1 is a perspective view of my improved gate.

Figure 2 is a side view of the latch-post for said gate.

Figure 3 is a view showing the arrangement of notch on latch-plate and wheel on end of latch.

Figure 4 is a plan of gear for operating the gate.

The nature of my invention consists in the peculiar combination of devices for opening and closing a farm-gate, said devices consisting of a sliding bar with gear on the side of it, which acts in combination with the gear on the gate-post, and opens and shuts said gate, and with a metal-plate attachment, which has a depression made on the under side of it, and which, acting in combination with a wheel on the end of the gate-latch, unlatches the gate when it is to be opened. The aforesaid sliding bar being operated by levers at the ends, which are so arranged that the gate can be opened or closed without getting out of the carriage, the whole being very cheap and simple, sure in its operations, and not liable to get out of repair.

To enable others skilled in the art to make and use my invention, I will proceed to describe its construction and operation.

The gate is of a common form, being constructed of bars G and H, rails I I, and brace R, as shown, and is hung on the gate-post B, as shown in fig. 1; or in any other suitable manner.

The gate-latch K is made of a strip of wood or iron, and is hung by a bolt, a, between the pieces L L, which are secured to the rails I I, as shown.

The front end of this latch works up and down in the slot Q in the gate-bar H, and catches in the notch P in the lower part of the notch O in the latch-post C, while the other end of said latch projects through the slot Q in the gate-bar G, and has the wheel R arranged on it, as shown.

The sliding bar E slides in a notch in the gate-post B, and is operated by the levers F F, the ends of which set in holes in the bar E, as shown, and to which they are attached by bolts b c, which pass through holes in these levers, the levers being pivoted to the posts A A by bolts f f, as shown.

This sliding bar E has the rack-gear M fastened on the side of it, which gears into the portion of a gear-wheel, N, on the gate-bar G, as shown in fig. 1, and in detail in fig. 4.

The metal-plate attachment D is bolted on the bar E, as shown, and has a depression, d, on the lower side of it, which, when the gate is shut, sets over the wheel R on the end of the latch K, as shown in figs. 1 and 3.

The operation of my gate is as follows:

When the gate is closed and is to be opened, one of the levers, F, is pulled to or from the gate, according to whether the gate is to be opened from or toward the operator.

The teeth on the rack M and pinion N are made so as to have a little play, as shown in fig. 4, thus allowing of a small sliding motion of the bar E, before the gate is acted on.

This sliding of the bar E causes a sliding of the plate D, and, by the action of the notch d, presses down the wheel R on the end of the latch K under said notch, and raises the other end of said latch from the notch P in the latch-post C, thus unlatching the gate.

The bar E, which carries the rack-gear M, being caused to slide by the action of the lever F, acts on the gear N on the gate-bar G, and forces the gate to swing open.

By reversing the action of said lever F, the gate will be closed, and the end of the latch K sliding up the inclined faces of the lower part of the notch O in the latch-post C, will drop into the notch P, and thus latch the gate.

What I claim as new, and desire to secure by Letters Patent, is—

The peculiar arrangement and combination of the gate G I H, gate-post B, gate-latch K, wheel R, latch-plate D, sliding bar E, rack and pinion M N, levers F F, and lever-posts A A, the several parts being arranged and combined in the manner and for the purposes specified.

As evidence that I claim the foregoing, I have hereunto set my hand in the presence of two witnesses, this 12th day of March, A. D. 1868.

CHRISTIAN RICH.
